UNITED STATES PATENT OFFICE.

JAMES B. ELLERY, OF ERIE, PENNSYLVANIA, AND ADAM DRUMTRA, OF BINGHAMTON, NEW YORK.

FIRE-EXTINGUISHING MATERIAL.

No Drawing.

Application filed December 13, 1921. Serial No. 522,148.

To all whom it may concern:

Be it known that we, JAMES B. ELLERY and ADAM DRUMTRA, citizens of the United States, and residents of Erie, in the county 5 of Erie and State of Pennsylvania, and Binghamton, in the county of Broome and State of New York, respectively, have invented certain new and useful Improvements in Fire-Extinguishing Materials, of 10 which the following is a specification.

Our invention relates to material adapted for extinguishing fires by providing an air-excluding blanket for the burning substance.

The invention is designed more particularly to provide a material for extinguishing fires in oil or other combustible liquid as for instance fires in oil tanks, although it may be likewise employed for fires of other inflammable liquids and either in 20 tanks or other situations.

Our invention consists essentially of a granular or sub-divided material capable, like cork, of floating on the surface of the liquid and rendered non-combustible in any 25 desired way. Preferably we treat the cork with a solution of silicate of soda which forms an actual coating and to some degree an impregnation of the cork and renders the same practically non-combustible, said 30 coating being retained on the cork when dry. This material, prepared beforehand, is stored in any convenient location ready for use and when occasion requires is thrown upon the burning liquid and by spreading 35 out and distributing itself over the surface of the liquid, forms a floating blanket of more or less uniform thickness which prevents access of air to the oil and thereby smothers the fire.

40 For handling material when it is desired to use it for extinguishing a fire, it may be stored in paper bags or other rupturable containers in which it may be conveyed to the scene of the fire and thrown upon the 45 same or, as will be obvious, any other mechanical means may be used for projecting the material over or upon the surface of the inflammable liquid to form the blanket.

The extent of granulation or sub-division 50 of the material may obviously be varied, the purpose being only that it be so far sub-divided as to form a blanket when spreading out upon the burning surface. Also, as will be obvious, other floating or buoyant

material might be employed instead of the 55 cork and properly coated with a coating of non-combustible or non-inflammable material which preferably should be such that it will dry on the surface of the sub-divided material and permit the same to be stored 60 in dry condition and thereafter to spread itself without adhesion or sticking together of the sub-divisions or granules when projected and freed for dispersion or distribution over such surface. 65

We do not limit ourselves to the employment of cork or any particular material coated with a non-inflammable substance since the essence of our invention consists in the use of a granulated material which is 70 both capable of floating and spreading over the surface of the inflammable liquid and is in itself, or is so prepared as to be, non-combustible or non-vaporizable by the action of the heat of the burning liquid or 75 other material.

While our invention is especially useful for extinguishing fires consisting of burning liquid, it obviously may be used for extinguishing fires of other burning materials. 80

The improved fire extinguishing material herein described and claimed is known as "Eldrex".

What we claim as our invention is:—

1. A buoyant non-combustible material in 85 granular or divided condition adapted to form an air-excluding blanket when spread over the surface of a burning body of liquid. 2. A fire extinguishing material comprising a granulated or sub-divided substance 90 like cork having a non-combustible non-vaporizable coating.

3. A fire extinguishing material comprising cork in granulated or sub-divided condition coated with silicate of soda. 95

4. The method of extinguishing fires in combustible liquids consisting in spreading over the surface of the same a mass of granular or sub-divided non-combustible material adapted to float upon and form an 100 air-excluding blanket over the surface of said liquid.

5. A fire extinguishing material comprising floating, non-combustible granular or sub-divided material. 105

6. A fire extinguishing material consisting of non-combustible, non-vaporizable material in granular or divided condition

adapted to float upon and form an air-excluding blanket upon a burning body of liquid.

State of Pennsylvania, this ninth day of December, A. D. 1921.

JAMES B. ELLERY.

HERMANN LEROY.

Signed at Binghamton, in the county of Broome and State of New York, this tenth day of December, A. D. 1921.

ADAM DRUMTRA.

Witnesses:

ELIZABETH DRUMTRA,
ELMER V. JACKSON.

7. A fire extinguishing material comprising cork or other buoyant substance in granular or sub-divided condition coated with a non-vaporizable coating.

8. A fire extinguishing material consisting of material in granular or divided condition, non-vaporizable and of specific gravity adapting it to float upon the surface of an inflammable liquid.

Signed at Erie, in the county of Erie and
